CARGO-CARRYING ROTARY WING AIRCRAFT AND THE LIKE

Geoffrey G. Clewlow, Huntington, N. Y., assignor
to Gyrodyne Company of America, Inc., Flower-
field, N. Y., a corporation of New York

Application November 14, 1951, Serial No. 17,411

Term of patent 14 years

(Cl. D71—1)

To all whom it may concern:

Be it known that I, Geoffrey G. Clewlow, a subject of the Queen of Great Britain, residing at Huntington, in the county of Suffolk and State of New York, have invented a new, original, and ornamental Design for Cargo-Carrying Rotary Wing Aircraft and the like, of which the following is a specification, reference being had to the accompanying drawing, forming part thereof.

In said drawing:

Fig. 1 is a plan of a cargo-carrying rotary wing aircraft, showing my new design.

Fig. 2 is a front side perspective view, showing the aircraft with cargo pod omitted.

Fig. 3 is a rear side perspective view showing

the carrier pod suspended below the lifting portion of the aircraft.

Fig. 4 is a rear side perspective view showing the carrier pod secured in flying position.

I claim:

The ornamental design for a cargo-carrying rotary wing aircraft and the like, as shown.

GEOFFREY G. CLEWLOW.
